[57] CLAIM

The ornamental design for a packaging container or similar article, substantially as shown and described.

DESCRIPTION

FIG. 1 is a front elevational view of a packaging container showing my new design;
FIG. 2 is an elevational view looking from the right of FIG. 1;
FIG. 3 is an elevational view looking from the left of FIG. 1;
FIG. 4 is a rear elevational view;
FIG. 5 is a top plan view; and
FIG. 6 is a bottom plan view thereof.
